UNITED STATES PATENT OFFICE.

MAURICE M. STRAUSS, OF CHICAGO, ILLINOIS.

GARMENT-HOLDER.

SPECIFICATION forming part of Letters Patent No. 756,074, dated March 29, 1904.

Application filed July 13, 1903. Serial No. 165,250. (No model.)

To all whom it may concern.

Be it known that I, MAURICE M. STRAUSS, a citizen of the United States, and a resident of Chicago, Cook county, Illinois, have invented 55
5 certain new and useful Improvements in Garment-Holders, of which the following is a full, clear, and exact description.

This invention has for its object, primarily, to provide an improved construction of garment-holder that shall serve, first, to retain 10
10 garments in proper position, more particularly within the shipping boxes or packages, and, second, which shall serve as a hanger for the garments after they have been removed 15
15 from the shipping boxes or packages.

The invention consists in the features of improvement hereinafter described, illustrated in the accompanying drawings, and more particularly pointed out in the claims at the end 20
20 of this specification.

I wish it distinctly understood, however, that while the primary object of my invention is to produce a garment-holder that can be used for retaining the shape of the garment 25
25 both in transportation and when removed from the shipping boxes or packages still it will be seen that features of the invention are susceptible of embodiment in garment holders or hangers of the type ordinarily employed 30
30 merely for suspending suits of clothing.

Figure 1 is a perspective view of a garment-holder embodying my invention. Fig. 2 is a plan view showing the position of the holder within a shipping-box.

35 In the preferred form of the invention the holder is made as a wire frame; but manifestly other material than wire may be employed without departure from the spirit of the invention.

40 As shown, the frame consists of the upper and lower sections A and B, that are adjustable with respect to each other. The top of the section A, which is adapted to set within the upper portions of a coat, is formed with the expanded shoulder portions a and a' , and from the outer ends of these shoulder portions a and a' lead, respectively, the wires a^2 and a^3 . The upper portions of the wires a^2 and a^3 are preferably bowed outward toward the armholes 45
45 of the coat within which the frame will be set.

The preferred manner of connecting the two sections of the frame together is by passing the side wires a^2 and a^3 of the upper section A through eyes or loops b , formed at the upper ends of the lower frame-section B, the lower ends of the wires a^2 and a^3 being formed with hooks or bent portions a^4 , that partially encircle the side wire b' of the lower frame-section. In this manner the sections A and B are made adjustable with respect to each other. 60
60 In order to enable the adjustment of the sections to be more readily secured, I prefer that the hooks a^4 at the ends of the wires a^2 and a^3 should be open hooks, and when the frame-sections are to be adjusted these hooks will 65 be disengaged from the side wires b' of the lower frame-section B, thereby permitting the frame-sections to be shifted freely with respect to each other, and when the sections are in the required position the hooked ends 70
70 a^4 will be again engaged with the side wires b' of the lower frame-section B. Preferably wire bands b^5 are secured to the side wires b' adjacent the loops b , and against these wire loops b^5 the wires a^2 and a^3 will bind when the hooks a^4 of these wires a^2 and a^3 are forced into engagement with the side wires b' of the lower frame-section B. 75
75

Across the top of the lower frame-section B extends the cross-bar b^2 , and across the bottom of this frame-section extends the bottom bar b^3 . Preferably the bars b^2 and b^3 are formed of wire and are connected to or formed in piece with the side wires b' of the frame-section B. 80
80

When a suit of men's clothing is to be packed for shipment, the upper section A of the garment-holder will be placed within the shoulder portions of the coat in the usual manner of a coat-hanger and the front of the coat and sleeves will be folded over the frame, the lower portion of the coat being turned upward around the bottom bar b^3 of the lower frame-section B. The trousers of the suit will be laid upon the bottom of the packing-box and will be folded around the bottom bar b^3 of the frame-section B and upon the outside of the coat. The waistcoat of the suit may be laid between the trousers and the coat, so as to retain it in position. The sec- 90

100

tions of my improved garment-holder will be adjusted so as to snugly fit within the shipping-box w , as shown in Fig. 2 of the drawings, and the adjustment of the sections adapts 5 the holder for shipping-boxes of different sizes.

When a suit of clothes is placed within the shipping-box as above described, it will be seen that the several articles of clothing will 10 be held in shape and be prevented from collapsing when the shipping-box is turned upon its sides or ends. Where suits of clothes are shipped without garment-holders, it is found that inasmuch as the shipping-boxes are in 15 transportation usually stood on edge the clothes when removed from the box are wrinkled and require to be pressed before used. By the employment of my improved garment- 20 holder the clothing is retained in shape during transportation regardless of the position in which the shipping-box may be placed.

When the suit of clothes is removed from the shipping-box, my improved garment-holder serves as a most effective means for 25 hanging the garments. The upper frame-section A serves as a coat and vest hanger in the usual manner, and for such purpose it is provided at its top with a hook C, attached centrally between the shoulder portions a and 30 a' of the hanger-section A, and the cross-bar b^2 serves as a support for the trousers, which will be hung across this bar.

If my improved garment-holder is formed 35 of wire, the hook C may be attached to an upwardly-extending loop a^5 , formed in the wire of which the upper part of the frame-section A is formed. The manner of forming the frame-sections of wire will be readily understood from the accompanying drawings, 40 and it will be understood also that the frame-sections could be formed of any other suitable material without departing from the spirit of the invention.

Having thus described my invention, what I

claim as new, and desire to secure by Letters 45 Patent, is—

1. A garment-holder, comprising an upper section formed with expanded shoulder portions a and a' and having wires a^2 and a^3 leading downwardly therefrom and rigid therewith and a lower section formed of side wires b' and bottom wires b^3 the side wires of the lower section being extensibly connected to the side wires of the upper section. 50

2. A garment-holder, comprising an upper section adapted to set within the shoulder portions of a coat and a lower section adjustably connected to said upper section, said lower section being provided at its top with a cross-bar adjustable therewith with respect to 60 said upper section.

3. A garment-holder, comprising an upper section adapted to set within the shoulder portions of a coat and having downwardly-extending side wires and a lower section adjustably connected to the side wires of said upper section and having a cross-wire carried 65 at its top and adjustable therewith toward and from the upper section.

4. A garment-holder formed of an upper 70 section having its upper portion adapted to set within the shoulder portions of a coat and a lower section extensibly connected to said upper section, said lower section being formed of side wires, a bottom wire and a top cross-bar, all of which are adjustable to and from 75 said upper section.

5. A garment-holder comprising an upper section formed of wire and having side wires provided with hooks at their ends and a lower 80 section formed of wire, said lower section being provided at its top with a cross-bar and having eyes or hooks through which the side wires of the upper section extend.

MAURICE M. STRAUSS.
